CLAIM

The ornamental design for a measuring-dispensing spoon or the like, substantially as shown and described.

DESCRIPTION

FIG. 1 is a side elevational view of a measuring-dispensing spoon or the like showing my new design, the side opposite being a mirror image thereof;

FIG. 2 is a top plan view thereof;

FIG. 3 is a cross-sectional view thereof taken on line 3—3 of FIG. 2; and

FIG. 4 is a top perspective view thereof.
